CLAIM

The ornamental design for the display screen with a graphical user interface, as shown and described.

DESCRIPTION

The file of this patent contains at least one drawing executed in color. Copies of this patent with color drawings will be provided by the Office upon request and payment of the necessary fee.

FIG. 1 is a front view of a first embodiment of a display screen with a graphical user interface showing the new design; and,

FIG. 2 is a front view of a second embodiment of a display screen with a graphical user interface showing the new design.

The dot-dash broken lines show the display screen and form no part of the claimed design. The dot-dot broken lines, illustrating all text and numerals shown within the graphical user interface, illustrate portions of the graphical user interface that form no part of the claimed design.
